UNITED STATES PATENT OFFICE.

WOLCOTT A. HULL, OF NEW YORK, N. Y.

DESIGN FOR A LAMP-FRAME.

SPECIFICATION forming part of Design No. 15,408, dated September 16, 1884.

Application filed May 16, 1884. Term of patent 7 years.

To all whom it may concern:

Be it known that I, WOLCOTT A. HULL, of New York, in the county of New York and State of New York, have invented and produced a certain new and original Design for Lamp-Frames, of which the following is a specification.

My invention and production relates to a hanging lamp; and the design consists in certain novel characteristics of the frame of such a lamp.

The accompanying illustration is a perspective view of a lamp-frame embodying my design.

15 The lower part of the lamp-frame consists

of two arc-shaped portions, *a*, shown as slightly eccentric to each other, and having between them scroll-like figures *b*, extending from a central circular fixture, *c*, to terminal circular figures *d*. From the circular figures *d* extend scroll-like bands *e*, and from these bands *e* sinuous bands *f* extend to a ring, *g*.

What I claim as my design, and desire to secure by Letters Patent, is—

The design for a lamp-frame, substantially 25 as described and shown.

WOLCOTT A. HULL.
